UNITED STATES PATENT OFFICE.

GUSTAF IVAR BARCLAY, OF DETROIT, MICHIGAN, ASSIGNOR TO DETROIT STEEL PRODUCTS CO., OF DETROIT, MICHIGAN, A CORPORATION OF MICHIGAN.

FASTENER FOR VENTILATORS.

Application filed May 26, 1924. Serial No. 716,040.

The invention relates to fasteners for ventilators and has for one of its objects the provision of an improved fastener in which the handle is frictionally held in its various positions of adjustment. Another object is to provide a fastener in which a common means frictionally engages the handle and forms a nut for the bolt upon which the handle is journaled. Further objects of the invention reside in the novel features of construction and combinations and arrangements of parts as more fully hereinafter set forth.

In the drawings:

15 Figure 1 is an inside elevation of a ventilator having applied thereto a fastener embodying my invention;

Figures 2 and 3 are enlarged cross-sections on the lines 2—2, and 3—3 of Figure 1;

20 Figure 4 is an enlarged outside elevation of a portion of the ventilator and fastener.

1 is the sash of the ventilator comprising side, top and bottom rails of substantially Z-shaped cross-section, each rail having an inner flange 2 forming a seat for the glass 3. 4 is the frame having the opening in which the ventilator is engageable for closing the same. The bars forming this frame are also preferably of substantially Z-shaped cross-section and arranged so that their flanges are engaged by the flanges of the sash rails when the ventilator is in closed position.

To secure the ventilator in closed position or a slightly open position, I have provided a fastener secured to the side rail of the sash at its swinging edge and engageable with the adjacent side bar of the frame. This fastener is so assembled that the support for the handle may lie in close proximity to the glass and the handle may be readily removed or applied without extra tools or danger of breaking the glass.

In detail, 5 is a bracket having the body 6 in the plane of and occupying an opening in the flange 2 of the side rail of the sash, the transverse flange 7 riveted to the web 8 of the side rail and the off-set flange 9 extending parallel to the body but laterally off-set inwardly therefrom. 10 is a handle having the boss 11 the inner side of which engages the off-set flange 9. 12 is a bolt extending through the boss 11 and the off-set flange 9 and upon which the handle is journaled. 13 is a laterally extending lug upon the handle near its journal and having an

end cam surface 14 movable over the side bar of the frame 4. 15 is a resilient yoke having one arm 16 enlarged at its end and located between the bolt head and the handle hub and the other arm 17 enlarged at its end and threadedly engaging the inner end of the bolt. This latter arm is located between the off-set flange 9 of the bracket and the glass 3. To retain the yoke from rotation relative to the bracket, the off-set flange 9 is cut away at 18 to be engaged in by the base or intermediate portion 19 of the yoke.

When the parts are assembled, the arms of the yoke are adjusted toward each other to place the yoke under compression, as a result the arm 16 as well as the off-set flange 9 frictionally engage the boss 11 of the handle to retain the latter in its various positions of rotative adjustment. Also this friction opposed to the rotation of the handle is constant, with the exception of decrease owing to wear, since the yoke is held from rotation. Another favorable result of this assembly is that the arm 17 of the yoke functions as a combined nut and lock washer owing to the fact that this arm threadedly engages the bolt 12 and has a tendency to spread away from the other arm, thereby placing an extra stress upon the inner sides of the bolt threads.

The laterally extending lug 13 is provided in its edge with the notch 20 for engagement in by the edge of inner flange of the frame side bar, whereby the ventilator may be held in slightly open position.

For the purpose of providing an improved bearing surface for engagement with the cam surface 14 of the laterally extending handle lug there is the rivet 21 upon the frame side bar. This rivet has the flattened head 22 located to be engageable by the cam surface.

To limit the rotation of the handle into fastening position I have provided the transverse pin 23 near the journal of the handle and engageable with the cut-away edge of the off-set flange 9 of the bracket.

From the above description it will be readily seen that I have provided an improved fastener which comprises but few parts and which is so formed that it may project but the minimum distance from the glass of the ventilator. Also the assembly of the fastener permits ready attachment or

- removal of the handle to or from its support without special tools and without danger of breaking the glass. Furthermore the construction opposes a constant frictional 5 resistance to rotation of the handle and the bolt upon which the handle is journaled or pivot for the handle is secured in place by a member which functions as a combined nut and lock washer.
10. What I claim as my invention is:
1. The combination of a support, a handle at one side of said support, a pivot for said handle extending through said handle and support and provided with a head at 15 one end and a threaded portion at the other end, and a resilient yoke embracing said handle and support and having a portion threadedly engaging said pivot threaded portion and another portion abutting said 20 pivot head.
  2. The combination of a support, a handle at one side of and engaging said support, a bolt extending through said handle and support, and a resilient yoke having a portion engaging the head of said bolt and said handle and another portion threadedly engaging said bolt at the opposite side of 25 said support.
  3. The combination of a support, a handle at one side of and engaging said support, a bolt extending through said handle and support, and a resilient yoke having one arm located between said handle and the head of said bolt and another arm threadedly 35 engaging said bolt at the opposite side of said support, and means for holding said yoke and support from relative rotation.
  4. In a ventilator the combination with a 40 sash having a side rail providing a seat for a glass, of a support upon said side rail having a portion off-set laterally from the glass, a handle at the opposite side of and engaging said off-set portion of the support, a bolt extending through said handle 45 and off-set portion, and a resilient yoke embracing said off-set portion and handle and having an arm located between the head of said bolt and said handle and another arm

threadingly engaging said bolt between said off-set portion and the glass. 50

5. The combination of a support, a handle, a bolt extending through said support and handle, and a member having a portion threaded upon said bolt at one side of said support and another portion at the opposite 55 side of said support and engaging said handle.

6. The combination of a support, a handle, a bolt extending through said support and handle and a member held from rotation by 60 said support and engaging said handle to offer frictional resistance to rotation of the latter, said member also engaging said bolt and offering frictional resistance to rotation of the same. 65

7. The combination of a support, a handle, a pivot upon said support for said handle, and a member having portions at opposite sides of said support and offering frictional resistance to rotation of said handle 70 relative to said support.

8. The combination of a support, a handle, a pivot upon said support for said handle and provided with a head, and a member having a portion engaging said support and 75 another portion between said head and handle.

9. The combination of a support, a handle, a pivot upon said support for said handle, and adjustable means embracing said support and handle and fixed against rotation with respect to said support for offering frictional resistance to rotation of said handle. 80

10. The combination of a support, a handle at one side of said support, a bolt extending through said support and handle, and a member secured to said bolt on the side of said support opposite said handle, said member extending around said support and handle for frictionally resisting rotation of said handle. 90

In testimony whereof I affix my signature.

G. IVAR BARCLAY.
